CASING PERFORATOR

Robert S. Smith, Whittier, Calif., assignor to
O. P. Yowell Service Company, a corporation
of California

Application April 27, 1936, Serial No. 76,567

8 Claims. (Cl. 81—188)

This invention has to do in a general way with perforators for well casing and is more particularly related to improvements in a perforator of the general type shown and described in United States Letters Patent No. 1,615,172, issued to D. W. Hoferer on January 18th, 1927.

As is well known to those familiar with the art, perforators of this general character are designed for use in penetrating or perforating oil well casing after it has been installed in a well, and the general construction followed in such perforators involves the use of a body member which carries a knife or cutter associated with means for advancing or swinging the same outwardly from the body into engagement with the casing wall to be perforated. In order that the perforator may be lowered into the casing without interference it is necessary that the knife or cutter be mounted so as to normally be contained within the body and since it is desirable that the knife reach as far as possible through the wall of the casing when it is extended, such knife must have a considerable length. These factors introduce several problems into the design 25 of a perforator of this character, chief of which involves the means for swinging the knife from the body in a manner such that it will bite into the wall of the casing so as to be driven through such wall by a downward driving force on the body.

In the Hoferer perforator referred to above, this is accomplished by employing a double-edged knife having one short point and one long point, the short point being adapted to initially engage the casing wall, the intention of such engagement being to offer sufficient resistance to the movement of the knife to cause the same to swing into a position at which the long blade will perforate the casing. In actual practice, however, I have discovered that with the Hoferer design the short blade has a greater tendency to skid along the casing during the downward driving force on the body so that it is at most merely effective to "marcel" or groove the casing metal.

It therefore becomes a primary object of this invention to provide means which are particularly adapted for use in a perforator of the Hoferer type which will positively support the cutter during downward movement of the body and through such support force the same into the wall of the casing a sufficient distance to insure the complete penetration of the casing as the body is subjected to further jarring or driving action.

After the blade has penetrated the casing in the manner just referred to above, it is impon-

tant that the body be capable of receiving further downward movement in order that the cutter may be fully extended and also permit the elongation of the perforation if this is desired.

It is, therefore, a further object of this invention to provide a cutter supporting member of the class just referred to which, after it has held the cutter against the casing under driving action on the body over a sufficient period to force the cutter well into or through the casing, will under continued driving force permit downward movement of the body and will itself move downwardly with respect to the casing.

The improvement contemplated by this invention embodies what I may term a tongue member which is slidably and pivotally mounted in the bottom portion of the groove which carries the cutter at its upper end, such tongue member being associated with anchor means for swinging same from the body.

It is a further object of this invention to provide means for automatically and positively withdrawing the tongue back into the body groove when the body is raised, thereby permitting the blade or cutter to fall freely back into the groove and also removing any projections which might catch on a projecting shoulder in the casing during the withdrawal of the tool.

The details in the construction of a preferred form of my invention, together with other objects attending its production will be best understood from the following description of the accompanying drawings which are chosen for illustrative purposes only and in which—

Fig. 1 is an elevational view showing a preferred form of perforator equipped with my invention;

Fig. 2 is an enlarged fragmentary sectional elevation taken in a plane represented by the line 2—2 of Fig. 1, and illustrates the parts in the position which they occupy while the tool is being withdrawn from the well;

Fig. 3 is an enlarged fragmentary sectional elevation similar to Fig. 2, but illustrating the parts arranged in the positions which they occupy at the start of a perforating operation;

Fig. 4 is a fragmentary sectional elevation taken in a plane represented by the line 4—4 of Fig. 2;

Fig. 5 is a sectional elevation taken in a plane represented by the line 5—5 of Fig. 2;

Fig. 6 is a plan section on the line 6—6 of Fig. 2;

Fig. 7 is a plan section on the line 7—7 of Fig. 2;

Fig. 8 is a plan section on the line 8—8 of Fig. 2; and

Fig. 9 is a plan section on the line 9—9 of Fig. 2. More particularly describing the invention as herein illustrated, reference numeral 11 indicates a perforator body equipped at its upper end with a sub 11' whereby it may be attached to suitable suspending and driving means such as a jar, not shown. The body 11 is shown as being provided with a longitudinal groove 12, the side faces of such groove being milled out as indicated at 10 13—13' to admit the reception of bosses 14 on a cutter member generally indicated by reference numeral 15. The bosses 14 on the cutter member are received in the inner offset ends 13' of the milled out slot 13—13' and are held in place 15 therein through the medium of retaining plates indicated at 16.

As best illustrated in Fig. 2, the cutter 15 is pivoted in the rear portion and at the upper end of the groove 12. This cutter, like the cutter of 20 the Hoferer patent above referred to is shown as having a long blade 18 and a short point 19. The short point 19 of this cutter, however, is not intended to have any substantial biting action on the casing, its function in holding the blade 25 being merely secondary in view of the improved blade supporting means contemplated by this invention. As will be observed from Figs. 2 and 3, the upper end of the slot 12 above the cutter is provided with an inclined face 20 which is engaged by the cutter when it is in its fully extended position shown in broken lines in Fig. 2. This inclined face may be formed during the 30 milling of the groove or it may be provided by the insertion of a block 21 which is shown as being 35 held in place by means of a pin 22.

The portion 12' of the groove 12 which extends downwardly below the region of the cutter 19 is shown as being widened so as to provide a shoulder 25 on the upper end of the section 12' of the 40 groove. On the two side faces of this widened portion 12' near its lower end, I provide aligned channels 26 which communicate with the outer face of the groove through slots 27. These channels 26 receive the ends of a cross pin 29 which is 45 mounted on the lower end of what I may term a tongue member 30, such tongue member being, through the medium of the pin 29, slidably and pivotally supported in the groove section 12'. The upper end of the tongue member 30 is provided with a downwardly inclined shoulder 31 and the outer face of this member below the 50 upper edge of the shoulder 31 is formed with a recess 32 within which a serrated wheel 33 is mounted upon a pivot pin 34. The rear portion 55 of the tongue member 30 is shown as being cut-away as indicated at 40 such cut-away portion including a groove section 41 shaped so as to provide an inclined face 41'.

It will be understood that, in the operation of 60 this tool, operative effect is given to the cutter by downward jarring movement applied to the body and the purpose of the tongue member as pointed out above is to provide a supporting surface which may be positively wedged against the casing with 65 sufficient force to swing the cutter 18 downwardly into engagement with the casing and to support such cutter during this engagement so that the cutter is positively driven through the wall of the casing by downward jarring action on the body. 70

The wedging action of the tongue member referred to above is accomplished through the medium of a shoe member 45 which has an inclined or wedged shaped face 46 adapted to engage the 75 face 41 on the tongue 30. This shoe 45 is mount-

ed on the upper end of a mandrel 49 which slidably extends through a passage 50 in a block 51, such block being secured in the bottom of the groove by means of cross pins 51'. This mandrel 49 carries at its lower end a friction tail piece or 5 any conventional type indicated by reference numeral 52.

For purposes of illustration, the tail piece 52 is shown herein as comprising an elongated sleeve section 53 having a shoulder 54 in its upper end 10 adapted to be engaged by a head 55 on the bottom of the mandrel. Mounted on the sleeve 53 at a substantial distance below the shoulder 54 is a collar 57 to which a plurality of flexible spring members 58 are secured at their upper ends, the 15 lower ends of such spring members being received in another collar 59 which is mounted on the bottom of the sleeve 53. In order that the tail piece 58 may be utilized to support the mandrel 59 against downward movement, and thereby 20 constitute such mandrel an anchor member, which will remain stationary during further downward movement of the body, it is necessary to provide a latch of some conventional type 25 whereby the tail piece and the mandrel can be locked against collapsing movement relative to each other. A preferred form of such latch is shown as comprising a finger member 61 pivoted to the collar 57 as indicated at 62 and adapted to swing through slots 63—64 in the upper end of 30 the sleeve 53. This finger member 61 is associated with a leaf spring 65 secured to the sleeve nut 54' by means of a screw 66, the spring being effective to bias the tongue inwardly toward its 35 horizontal position.

In the operation of the perforator contemplated by this invention, the leaf spring assembly and the mandrel are drawn to their fully extended positions, the finger 61 is raised to its vertical position and is pressed outwardly against the 40 action of the spring 65 after which the spring assembly is moved upwardly on the mandrel so as to assume the position shown in Fig. 1. The spring assembly is then inserted into the casing 45 its resistance therein being sufficient to hold the same against the body as shown in Fig. 1 and the weight of the mandrel at the same time is sufficient to hold it in its lowermost position as illustrated in Fig. 2. In this position it will be observed that the lower end of the shoe 45 engages a 50 shoulder 68 formed in the bottom of the groove 40 on the tongue and through such engagement holds the tongue in its retracted position.

The weight of the cutter and the manner in 55 which it is pivoted maintains the cutter in retracted position so that it is entirely enclosed within the groove of the body. When the perforator arranged in this manner has been lowered into the well to the point at which it is desired to effect a perforating operation, the body is raised by applying tension through the connection 12, such raising action being effective to lift the head 55 on the mandrel to a point at which its lower edge clears the upper edge of the finger 61. The 60 spring 65 then swings the finger 61 into its horizontal position as shown in Fig. 2 and the perforator body is then lowered.

During this lowering movement the mandrel 49 and the shoe 45 remains stationary so that as the 70 body moves downwardly the face 41 on the tongue comes into engagement with the face 46 on the shoe. The tongue is thereby supported against further downward movement relative to the body such movement of the body taking place by virtue 75

of the pin and slot connection 29—26. As this downward movement of the body continues the lower edge of the blade 18 comes in contact with the shoulder 31. As movement is continued from this point, the wedging action between the faces 41 and 46 on the tongue and the shoe respectively cause the tongue to swing outwardly from the body bringing the sharp corners on the serrated wheel 33 into engagement with the wall of the casing. The cutter 15 also swings outwardly during this movement so that the short point 19 also engages the casing. Due to the wedging action between the faces 41—46 further jarring action on the body causes the sharp corner on the wheel 33 to bite into the wall of the casing providing a stationary member against which the long point 18 of the knife is driven. This stationary unit forces the knife from the position shown in full lines in Fig. 3 into the position shown in broken lines in Fig. 3 where it will be observed that the blade has been forced through the wall of the casing.

When this position has been reached, in the form of my invention shown herein, the shoulder 25 has been lowered into engagement with the shoulder 31 on the tongue and the blade has penetrated the casing a sufficient distance to be carried on to its fully extended position by continued downward driving action on the body. It is important, therefore, that the holding means associated with the tongue 39 be of a nature such as to permit further downward movement of the body under this continued driving action and this is accomplished through the use of a serrated wheel which will, under such continued driving action tend to rotate as contrasted with a positive gripping member such as a slip. In this connection, it will be observed that up until such time as the shoulder 25 engages the top of the tongue, there is no direct driving force applied to the tongue. The serrated wheel being wedged into the wall of the casing where the force required to cause it to rotate must be greater than the force necessary to swing the blade through the casing. The downward driving force up to this point, therefore, is effective to bring the fulcrum of the blade down toward the top of the tongue.

When the perforation has been completed and it is desired to raise the perforator either to effect a perforation at a higher point or withdraw it from the well, it will be observed that when lifting force is applied to the body the shoe 46 will be held against movement through frictional engagement of the springs 58 with the wall of the casing, such springs acting upon the shoe through the medium of the mandrel and the head 55. With this arrangement as the body raises the tongue to a point at which the shoulder 68 engages the underside of the shoe, such engagement will automatically snap the tongue back into its vertical position where it is entirely enclosed within the groove thereby removing any projected surfaces which might cause the perforator to be held up by shoulders within the casing.

It is to be understood that while I have herein described and illustrated one preferred form of my invention that the invention is not limited to the precise construction described above, but includes within its scope whatever changes fairly come within the spirit of the appended claims.

I claim as my invention:

1. In a casing perforator having a longitudinally grooved body with a cutter pivotally mounted in the upper end of said groove, means for swinging said cutter from said groove into en-

gagement with a casing and maintaining such engagement during an initial downward movement of said body comprising: a tongue member slidably and pivotally mounted in the bottom portion of said groove; a shoe slidably mounted in said groove behind said tongue and adapted to simultaneously support said tongue against downward movement and swing the same outwardly from said body during downward movement of said body relative to said shoe; means on said tongue for biting into a casing when the tongue is forced outwardly by said shoe; and a shoulder on the top of said tongue for forcing said cutter into the wall of a casing during downward movement of said body relative to said tongue. 15

2. In a casing perforator having a longitudinally grooved body with a cutter pivotally mounted in the upper end of said groove, means for swinging said cutter from said groove into engagement with a casing and maintaining such engagement during an initial downward movement of said body comprising: a tongue member slidably and pivotally mounted in the bottom portion of said groove; a shoe slidably mounted in said groove behind said tongue and adapted to simultaneously support said tongue against downward movement and swing the same outwardly from said body during downward movement of said body relative to said shoe; means comprising a serrated wheel mounted in said tongue and projecting outwardly therefrom, for biting into a casing when the tongue is forced outwardly by said shoe; and a shoulder on the top of said tongue for forcing said cutter into the wall of a casing during downward movement of said body relative to said tongue. 35

3. In a casing perforator having a longitudinally grooved body with a cutter pivotally mounted in the upper end of said groove, means for swinging said cutter from said groove into engagement with a casing and maintaining such engagement during an initial downward movement of said body comprising: a tongue member slidably and pivotally mounted in the bottom portion of said groove; a shoe slidably mounted in said groove behind said tongue and adapted to simultaneously support said tongue against downward movement and swing the same outwardly from said body during downward movement of said body relative to said shoe; means on said tongue for biting into a casing when the tongue is forced outwardly by said shoe; a shoulder on the top of said tongue for forcing said cutter into the wall of a casing during downward movement of said body relative to said tongue and means at the bottom of said tongue adapted to be engaged by said shoe in its lowermost position for holding said tongue in a retracted position. 55

4. In combination with a casing perforator having a longitudinally grooved body and a cutter pivotally mounted in the upper end of the groove therein, means for swinging said cutter into the wall of a casing during downward movement of said body comprising: a tongue member slidably and pivotally mounted in the bottom portion of said groove; a shoe slidably mounted in said groove behind said tongue, said shoe and tongue having faces adapted for wedging engagement upon downward movement of said tongue relative to said shoe whereby said tongue is swung outwardly from said body; means on said tongue for biting into a casing when said wedging faces are in engagement; friction means associated with said shoe and engageable with 75

- a casing to hold said shoe against downward movement; and a shoulder on the upper end of said tongue adapted to be engaged by said cutter for swinging said cutter during downward movement of said body relative to said tongue.
5. In combination with a casing perforator having a longitudinally grooved body and a cutter pivotally mounted in the upper end of the groove therein, means for swinging said cutter into the wall of a casing during downward movement of said body comprising: a tongue member slidably and swingably mounted in the bottom portion of said groove; casing gripping means mounted near the upper end of said tongue; a shoulder on said tongue engageable with said cutter for swinging said cutter from said body during downward movement of said body relative to said tongue; and means including an anchor member slidably supported by said body and engageable with a casing for simultaneously supporting said tongue against downward movement and swinging same from said groove.
6. In combination with a casing perforator having a longitudinally grooved body and a cutter pivotally mounted in the upper end of the groove therein, means for swinging said cutter into the wall of a casing during downward movement of said body comprising: a tongue member slidably and swingably mounted in the bottom portion of said groove; a serrated wheel rotatably mounted in said tongue near the upper end thereof with a portion projecting therefrom for biting into the wall of a casing when said tongue is swung from said body; a shoulder on said tongue engageable with said cutter for swinging said cutter from said body during downward movement of said body relative to said tongue; and means including an anchor member slidably supported by said body and engageable with a casing for simultaneously supporting said tongue against downward movement and swinging same from said groove.
7. In combination with a casing perforator

having a longitudinally grooved body and a cutter pivotally mounted in the upper end of the groove therein, means for swinging said cutter into the wall of a casing during downward movement of said body comprising: a tongue member slidably and swingably mounted in the bottom portion of said groove; casing gripping means mounted near the upper end of said tongue; a shoulder on said tongue engageable with said cutter for swinging said cutter from said body during downward movement of said body relative to said tongue; and means including an anchor member slidably supported by said body and engageable with a casing for simultaneously supporting said tongue against downward movement and swinging same from said groove said last mentioned means including a wedging shoe slidably mounted in said groove behind said tongue.

8. In combination with a casing perforator having a longitudinally grooved body and a cutter pivotally mounted in the upper end of the groove therein; means for swinging said cutter into the wall of a casing during downward movement of said body comprising: a tongue member slidably and swingably mounted in the bottom portion of said groove; casing gripping means mounted near the upper end of said tongue; a shoulder on said tongue engageable with said cutter for swinging said cutter from said body during downward movement of said body relative to said tongue; and means including an anchor member slidably supported by said body and engageable with a casing for simultaneously supporting said tongue against downward movement and swinging same from said groove said last mentioned means including a shoe member slidably mounted in said groove behind said tongue, and said tongue having a shoulder at its lower end adapted to be engaged by said shoe upon upward movement of said body relative to said anchor member for withdrawing said tongue into said groove.

ROBERT S. SMITH.
